S. B. Bair

By Alexander Snider

UNITED STATES PATENT OFFICE.

ALLEN J. SNIDER AND SILAS B. BAIR, OF KEOTA, IOWA.

BUTTER-WORKER.

SPECIFICATION forming part of Letters Patent No. 247,702, dated September 27, 1881.

Application filed February 23, 1881. (No model.)

To all whom it may concern:

Be it known that we, ALLEN J. SNIDER and SILAS B. BAIR, of Keota, in the county of Keokuk, and in the State of Iowa, have invented 5 certain new and useful Improvements in Butter-Workers; and we do hereby declare that the following is a full, clear, and exact description thereof, reference being had to the accompanying drawings, and to the letters of reference 10 marked thereon, making a part of this specification.

This invention relates to certain improvements in butter-workers; and it has for its objects to provide an apparatus by means of which 15 a mass or body of butter may be thoroughly worked and the water allowed to escape therefrom. These objects we attain by the apparatus and mechanism illustrated in the accompanying drawings, in which—

20 Figure 1 represents a side elevation of our improved apparatus; and Fig. 2 represents a transverse vertical sectional view of the apparatus.

In the drawings, the letter A indicates the 25 base of the apparatus, which is provided with the vertical standards B, in which the crank-shaft C, which operates the workers or pressers, is journaled.

The letter D indicates the workers or pressers, which consist of transverse bars secured 30 to the vertically-reciprocating bars E, which are arranged to reciprocate in the horizontal guide-bars F, secured to the standards B. The said reciprocating bars are connected with the 35 cranks on the shaft by means of the links H, the cranks being so arranged as to reciprocate the said bars alternately. The crank-shaft is provided with a fly-wheel, I, and band-pulley

K, by means of the latter of which power may be applied to operate the workers, and also 40 with a winch at one end, by which the apparatus may be worked by hand. The workers or pressers at each side are corrugated on their lower faces, and the intermediate one is beveled on its lower face, as shown. 45

The letter M indicates the butter-receptacle, which consists of an inclined open rectangular box mounted upon suitable legs, which elevate it to the proper position. At the lower side of the box is a longitudinal aperture, N, for the 50 escape of water. The pressers have the same inclination as the bottom of the box. The legs are provided with grooved rollers P, which set upon the rails R, whereby the box may be moved back and forth, so that the whole mass 55 of butter may be thoroughly worked.

Having thus fully described our invention, what we claim, and desire to secure by Letters Patent, is—

In combination with the frame B and base 60 A, the crank-shaft C, links H, reciprocating bars E, guides F, workers D, the table M, having an inclined bottom and opening N, and mounted on flanged rollers P, adapted to travel on rails secured to the base A, the whole arranged to operate substantially in the manner 65 specified.

In testimony that we claim the foregoing we have hereunto set our hands this 7th day of February, 1881.

A. J. SNIDER.
S. B. BAIR.
